UNITED STATES PATENT OFFICE.

JAMES TIMMS, OF COLUMBUS, OHIO.

DESIGN FOR A LOCKING-BLOCK FOR CAR-COUPINGS.

SPECIFICATION forming part of Design No. 34,972, dated August 20, 1901.

Application filed June 25, 1901. Serial No. 66,012. Term of patent 14 years.

To all whom it may concern:

Be it known that I, JAMES TIMMS, of Columbus, in the county of Franklin and State of Ohio, have invented and produced a new and original Design for Locking-Blocks for Car-Couplings; and I do hereby declare the following to be a full, clear, and exact description of the invention, such as will enable others skilled in the art to which it appertains to make and use the same.

In the accompanying drawings, Figure 1 is a perspective view of the locking-block. Fig. 2 is a horizontal cross-sectional view. Fig. 3 is a rear view.

The locking-block consists of a mass of metal larger at its upper than at its lower end, the upper portion 1 being approximately square and having an upwardly-projecting flange 2 at one edge. From the top face of the portion 1 an eye projects. Below the upper portion 1 is a recess 4, the top wall of which is formed by the under face of the upper portion 1 of the block, which thus forms a shoulder 5. One side wall 6 of the recess is slightly inclined or beveled outwardly, and below the upper portion 1 the block has a downwardly-inclined portion 7. Below the recess 4 the block has a diagonal

face 8, and above this diagonal face the metal of the block protrudes outwardly beyond the same, as at 9, and forms a shoulder 10, one side of said protruding portion also forming one wall of the recess 4. Below the shoulder 10 and at one edge of the diagonal face 8 the block is beveled, as at 11. At the lower end of the diagonal face 8 and extending from the beveled portions 7 and 11 is an outwardly-projecting nose 12, the end 13 of which is rounded and the upper face 14 inclined transversely, the bottom edge of the block constituting the lower end of the face 14 of the nose. The portions of the mass of metal constituting the block which have not been above described consist of flat faces 15.

Having fully described my design, what I claim as new, and desire to secure by Letters Patent, is—

The design for a locking-block for car-couplings herein shown and described.

In testimony whereof I have signed this specification in the presence of two subscribing witnesses.

JAMES TIMMS.
